F. W. MOFFAT,
SECTIONAL ELECTRIC HEATING ELEMENT,
APPLICATION FILED APR. 12, 1918.

1,276,096.

Patented Aug. 20, 1918.

UNITED STATES PATENT OFFICE.

FREDERICK W. MOFFAT, OF WESTON, ONTARIO, CANADA.

SECTIONAL ELECTRIC HEATING ELEMENT.

1,276,096.

Specification of Letters Patent. Patented Aug. 20, 1918.

Application filed April 12, 1918. Serial No. 228,229.

To all whom it may concern:

Be it known that I, FREDERICK W. MOFFAT, of the town of Weston, in the county of York, Province of Ontario, Canada, have 5 invented certain new and useful Improvements in Sectional Electric Heating Elements, of which the following is a specification.

This invention relates to heating elements 10 specially adapted for heavy duty in hotels and restaurants and for other commercial work requiring large heating surface with three heats, and my object is to devise means whereby an element can be built up of 15 standard parts to any desired width and length to suit the requirements of any particular customer.

I attain my object by means of the constructions hereinabove described and illustrated in the accompanying drawings in which—

Figure 1 is a plan view of part of an 20 electric heating element built up according to my invention;

Fig. 2 a section along the line *a—a* in Fig. 1;

Fig. 3 an elevation of the outer face of one of the end members;

Fig. 4 a section on the line *b—b* looking 30 toward the left hand side of Fig. 1.

In the drawings like numerals of reference indicate corresponding parts in the different figures.

1 is a slab of refractory insulating material such as commonly employed in the manufacture of electric heating elements. 35 This slab is provided in its upper surface with parallel grooves 2 extending through its ends. These grooves are preferably provided with the ribs 3 in their bottoms, as in the prior United States Patent No. 1195828 of August 22nd, 1916, granted to Lewis R. McClatchie, and also with lugs or projections 4 intended to hold down the resistance wires in the grooves. These features, however, form no part of the present invention.

5 is an end bar provided with holes 6 adapted to align with the grooves of the 50 slab. 7 is an end bar also provided with holes 6 adapted to align with the grooves of the slab. In each end bar are formed grooves 8 connecting alternate holes 6, said grooves passing alternately above and below alternate holes. The grooves in one bar are in staggered relationship to those in the

other bar as will be seen particularly on reference to Figs. 3 and 4 of the drawings.

As the resistance wire is preferably formed in two separate circuits to give three 60 heats and it is desired that the terminals shall be at one end, I employ an even number of the grooves 8, and at least four, eight being the preferable number. As it is intended to employ a plurality of the slabs I 65 arranged side by side as well as end to end, it is necessary to form parts of grooves 8 at each of one of the end bars. With the arrangement shown, these parts of grooves are located in the end bar 5, so that when a 70 second end bar is placed end to end with it as illustrated in Fig. 1, a complete groove is formed. Through the grooves 8 the resistance wires are connected as illustrated.

Each end bar 5 has an outwardly extending flange 9 formed integral therewith, and through this flange are bolted the terminals 75 10. One terminal at one end of the bar is intended to form a common terminal for both circuits of the resistance wire, while 80 the other terminals form independent connections for the two circuits, as is common in the art.

Preferably a boss 11 is formed integral with the under side of the bar 5, through 85 which the common terminal extends, and also a boss 12 through which both of the other terminals extend. Through the flange 9 and through the bosses are formed holes 13, through which the wires connecting 90 with the resistance are led and connected with the terminals.

When the wires are so connected, a filling piece 14 is fitted over the flange 9 and against the side of the bar 5, so as to come 95 flush with the outer side of the flange and top of the bar. All connections are then completely covered and the possibility of accidental short circuiting is avoided.

The slabs and end bars are fitted into a 100 metal pan 15 of suitable dimensions to contain one or more slabs in length and one or more slabs in width plus the end bars. In the bottom of the pan is laid a quantity of kieselguhr or other heat insulating material 105 and above this slabs of insulating material 16 of sufficient thickness so that the upper sides of the slabs and end bars are just below the top of the pan. Holes are formed in the bottom of the pan for the passage of 110 the bosses 11 and 12, so that the terminals are exposed below the pan for making the

necessary connections with the switches. A metal plate 17 is fitted on and secured to the edges of the pan.

From the constructions described, it will be seen that I have devised a construction which will enable a heating element of any desired size or capacity to be built up from standard parts, as any desired number of slabs 1 can be fitted end to end and side to side, and the necessary number of end bars employed to correspond with the number of slabs which lie side by side. The only parts requiring to be made of different sizes are the pans in which the element is received and the metal plates 17 which forms the top of the element and on which the cooking is performed.

What I claim as my invention is:—

1. In a sectional electric heating element, the combination of a slab of insulating material having parallel grooves for the reception of resistance wire formed in its upper surface and extending through its ends; and separate end bars of insulating material in length substantially equal to the width of the slab, fitted closely thereto, and having holes formed therein adapted to align with the grooves of the slab, grooves being formed in the outer surface of each bar connecting alternate holes, said grooves passing alternately above and below alternate holes, and the grooves in one bar being in staggered relationship to those in the other bar.

35 2. In a sectional electric heating element, the combination of a slab of insulating material having an even number of, and at least four, parallel grooves for the reception of resistance wire formed in its upper surface and extending through its ends; and separate end bars of insulating material in length substantially equal to the width of the slab, fitted closely thereto, and having holes formed therein adapted to align with the grooves of the slab, grooves being formed in the outer surface of each bar connecting alternate holes, said grooves passing alternately above and below alternate holes, and the grooves in one bar being in 50 staggered relationship to those in the other bar.

3. In a sectional electric heating element, the combination of a slab of insulating material having parallel grooves for the reception of resistance wire formed in its upper surface and extending through its ends; separate end bars of insulating material in length substantially equal to the width of the slab, fitted closely thereto, and having holes formed therein adapted to align with the grooves of the slab, grooves being formed in the outer surface of each bar connecting alternate holes, said grooves passing alternately above and below alternate holes, and the grooves in one bar being in 65 staggered relationship to those in the other bar.

staggered relationship to those in the other bar; an outwardly extending flange formed on one of the end bars below the holes; terminal posts secured through said flange, holes for the passage of the ends of the resistance wire being formed through said flange from top to bottom.

4. In a sectional electric heating element, the combination of a slab of insulating material having parallel grooves for the reception of resistance wire formed in its upper surface and extending through its ends; separate end bars of insulating material having holes formed therein adapted to align with the grooves of the slab, grooves being formed in the outer surface of each bar connecting alternate holes, said grooves passing alternately above and below alternate holes, and the grooves in one bar being in staggered relationship to those in the other bar; an outwardly extending flange formed on one of the end bars below the holes; terminal posts secured through said flange, holes for the passage of the ends of the resistance wire being formed through said flange from top to bottom; and a filling piece of insulating material adapted to fit above the flange.

5. In a sectional electric heating element, the combination of a slab of insulating material having parallel grooves for the reception of resistance wire formed in its upper surface and extending through its ends; separate end bars of insulating material having holes formed therein adapted to align with the grooves of the slab, grooves being formed in the outer surface of each bar connecting alternate holes, said grooves passing alternately above and below alternate holes, and the grooves in one bar being in staggered relationship to those in the other bar; an outwardly extending flange formed on one of the end bars below the holes; integral bosses depending from the flange; terminal posts secured through said flange and bosses, holes for the passage of the ends of the resistance wire being formed through said flange and bosses from top to bottom.

6. In a sectional electric heating element, the combination of a slab of insulating material having parallel grooves for the reception of resistance wire formed in its upper surface and extending through its ends; separate end bars of insulating material in length substantially equal to the width of the slab, fitted closely thereto, and having holes formed therein adapted to align with the grooves of the slab, grooves being formed in the outer surface of each bar connecting alternate holes, said grooves passing alternately above and below alternate holes, and the grooves in one bar being in staggered relationship to those in the other bar; a metal pan into which the slab and bars are fitted; insulating material in the bottom of

the pan on which the slab and bars rest; and a metal cover plate resting on the edges of the pan.

7. In a sectional electric heating element, 5 the combination of a slab of insulating material having parallel grooves for the reception of resistance wire formed in its upper surface and extending through its ends; 10 separate end bars of insulating material having holes formed therein adapted to align with the grooves of the slab, grooves being formed in the outer surface of each bar connecting alternate holes, said grooves passing alternately above and below alter- 15 nate holes, and the grooves in one bar being in staggered relationship to those in the other bar; an outwardly extending flange

formed on one of the end bars below the holes; integral bosses depending from the flange; terminal posts secured through said flange and bosses, holes for the passage of the ends of the resistance wire being formed through said flange and bosses from top to bottom; a metal pan into which the slab and bars are fitted; insulating material in the bottom of the pan on which the slab and bars rest; and a metal cover plate resting on the edges of the pan, holes being formed in the bottom of the pan for the passage of the lower ends of the bosses aforesaid. 20 25 30

Signed at Toronto, Canada, this 3rd day of April, 1918.
